SPRAY HEAD

Martin De Graaf, Grand Rapids, Mich.

Application March 1, 1934, Serial No. 713,501

5 Claims. (Cl. 299—58)

The present invention relates to spray heads and more particularly to vaporizing units adapted for use in conjunction with vegetable display stands or for use in air humidification.

5 The principal objects of the invention are to provide a spray head of the character above indicated having adjusting means for directionally controlling the flow of the vaporized moisture; to provide such a device having adjusting means 10 for controlling the amount of water it is desired to vaporize; and, to provide such a device which is attractive in appearance, economical in manufacture and highly efficient in use.

An illustrative embodiment of the invention is 15 shown in the accompanying drawings, wherein:

Figure 1 is a perspective view of a vegetable display stand adapted for use in retail grocery stores and provided with the spray head of the instant invention;

20 Figure 2 is a transverse sectional view thereof; Figure 3 is an enlarged view of the spray head housing showing its water vapor emitting opening;

25 Figure 4 is an enlarged view of the spray head assembly, portions thereof being in longitudinal section and other portions being broken away to better show its structural and functional characteristics;

Figure 5 is a sectional view of the spray head 30 housing on lines 5—5 of Figures 3 and 4;

Figure 6 is a sectional view on line 6—6 of 35 Figure 4;

Figure 7 is a sectional view on line 7—7 of Figure 4; and

35 Figure 8 is an enlarged longitudinal sectional view on line 8—8 of Figure 4.

Referring then to the drawings in which like parts of the structure shown are designated by the same numerals in the several views, a display 40 stand 10 is provided with an angularly disposed screened top 11 for supporting displayed vegetables. A supply conduit 12 connected with any suitable source of water supply under pressure is preferably disposed beneath the wire screening 45 parallel thereto and running substantially the length of the display stand and medially of its width.

A plurality of spaced vertically disposed auxiliary water supply conduits 13 are connected with 50 the main conduit 12 as by T-unions 14 and project above the wire screening. The upper end of each conduit 13 is preferably provided with a valve fitting 15 for housing the valve 16 which may be adjustably controlled by the manually operable knurled head 17. This valve fitting is pro-

vided with a vertically projecting water emitting head 18 which is here shown as externally screw threaded for receiving the internally screw threaded nozzle retaining cap 19.

Spacedly encircling each auxiliary conduit 13 5 is a drain conduit 20 for draining waste water therethrough and through the drain ports 21 in the valve fitting 15 on opposite sides of the valve 16 and through the drain ports 22 on opposite sides of the T-unions 14 into the base of the display stand which may be provided with a drain pipe 23 here shown as at one end of the stand. 10

An annular gasket 24, preferably of rubber or of some other resilient material, and whose upper surface is concave is disposed within the cap 19 15 whose under surface is likewise concave. A nozzle comprising an elongated member 25 is provided with a longitudinal bore 26 and with a spherical portion 27 adapting the spherical portion to be seated in the socket formed by the oppositely disposed concave surfaces of the gasket 24 and cap 19. A ball and socket joint is thus formed between the nozzle and its conduit and permits of a limited angular adjustment of the nozzle relative to its conduit for directionally controlling the 25 emitted water spray. The upper end of the nozzle is externally screw threaded and a cap 28 therefor is internally screw threaded for retaining the resilient element 29 and the spray forming element 30 which is provided with a bore 31 30 of a very small diameter, all as best shown in Figure 8. The spray forming element 30 is preferably of glass which is non-corrosive and the water emitting bore 31 is thus maintained open and free of corrosion. By providing a nozzle with 35 the elongated member 25 which is tapered at the inlet end thereof, sediment and other relatively large foreign matter carried by the water through the conduit 13 are less likely to be passed through the longitudinal bore 26 of the nozzle to clog 40 the bore 26. In other words, such foreign matter is more likely to pass beyond the intake opening or orifice of the longitudinal bore in the portion 25 of the nozzle upwardly toward the inner surface of the cap 19. 45

Mounted at the upper end of each drain conduit 20 is a spray head housing comprising the rigidly secured funnel portion 32 and the dome portion 33 which is supported by the vertically 50 disposed rods 34 secured to the annular ring 40 which is mounted in vertically adjustable screw threaded engagement with the drain conduit. By rotating the knurled head of the dome portion 33, the width of the vapor emitting opening may 55

be varied for adjustably controlling the vapor flow therethrough.

A vaporizing baffle 36 against whose under surface the spray from the nozzle impinges is suspended from the dome portion 33 as by the ball and socket connection between the head 37 and the upper surface of the dome portion. A coiled expansion spring 38 surrounding the shank 39 and interposed between the baffle plate and the under side of the dome portion of the spray head housing is provided so that the baffle may be maintained in its angularly adjusted position to further directionally control the flow of the water vapor emitted through the opening 35.

In operation, water under pressure flowing through the water supply conduit 12 is supplied to the auxiliary conduits 13 and the amount flowing therethrough may be controlled by the manually operable valve 16. As the water is emitted through the nozzle orifice 31, a fine spray is formed which impinges upon the baffle 36 causing the spray to vaporize and pass through the spray emitting opening 35 of the spray head housing. The water vapor is thus adaptable for use either in maintaining vegetables supported on the display stand in a fresh condition or as a humidifier for humidification purposes. Water which is not thoroughly vaporized is permitted to flow back through the drain conduit 20 into the base of the display stand and thence out through the drain pipe 23.

Either or both the nozzle and baffle may be manually angularly adjusted for directionally controlling the water vapor emitted through the opening of the spray head housing as hereinbefore described and it will thus be seen that the device is not only attractive in appearance and economical in manufacture but is highly efficient in use.

While but one specific embodiment of this invention has been herein shown and described, it

will be understood that numerous details of the construction shown may be altered or omitted without departing from the spirit of this invention as defined by the following claims.

I claim:

1. In a structure of the class described, a water supply conduit having an angularly adjustable nozzle, a housing associated with respect to the conduit spacedly encircling the nozzle and provided with a vapor emitting opening, and a vaporizing baffle secured to and depending within the housing.

2. In a structure of the class described, a water supply conduit having an angularly adjustable nozzle, a housing associated with respect to the conduit spacedly encircling the nozzle and provided with a vapor emitting opening, and an angularly adjustable vaporizing baffle secured to and depending within the housing.

3. In a structure of the class described, a water supply conduit having a nozzle, a housing associated with respect to the conduit spacedly encircling the nozzle and provided with a vapor emitting opening, and an angularly adjustable vaporizing baffle secured to and depending within the housing.

4. In a device of the class described, a spray head, an angularly adjustable vaporizing baffle, and a housing for the spray head and vaporizing baffle having a vapor emitting opening which is adjustable as to its width.

5. In a structure of the class described, a water supply conduit provided with a nozzle, a housing associated with respect to the conduit spacedly encircling the nozzle, a dome spacedly associated with the housing axially adjustable relative thereto to form a vapor emitting opening adjustable as to its width, and an angularly adjustable vaporizing baffle within the housing.

MARTIN DE GRAAF.
